Primary Examiner — Mark A Goodwin

(57) **CLAIM**

The ornamental design for an agricultural robot as shown and described.

DESCRIPTION

1. Agricultural robot

1.1 : Perspective

1.2 : Rear perspective view

1.3 : Front

1.4 : Back

1.5 : Left

1.6 : Right

1.7: Top

1.8: Bottom

The broken lines in the drawings, and the deemphasized portions within, illustrate portions of the agricultural robot that form no part of the claimed design.
